UNITED STATES PATENT OFFICE

JAMES G. BAUDINO, OF MILFORD, UTAH

PINON NUT SHELLER

Application filed May 24, 1928. Serial No. 280,262.

This invention relates to a pinon nut sheller.

An important object of the invention is the provision of a device for removing the shells from pinon nuts which is of such character that the shells will be so broken that they may be readily separated from the nuts and, at the same time, a very low percentage of the nuts are crushed or otherwise rendered unfit for use.

A further object of the invention is to provide a device of this character which may be very readily and cheaply manufactured and which will be durable and efficient in service.

A still further object of the invention is to provide a structure for removing thin brittle shells from nuts including a rotating burr element and a stationary burr element between which the nuts are passed to rupture the shells thereof, the structure of the stationary burr element being such that a new surface may be quickly presented for service when, in use, the burrs of such stationary element become worn or are otherwise destroyed.

These and other objects I attain by the construction shown in the accompanying drawings, wherein for the purpose of illustration is shown a preferred embodiment of my invention and wherein:

Figure 1 is a side elevation of a pinon nut sheller constructed in accordance with my invention;

Figure 2 is a plan view thereof with the hopper removed;

Figure 3 is a longitudinal sectional view therethrough;

Figure 4 is a detail sectional view through the stationary roll element;

Figure 5 is a detail sectional view showing the manner of securing the hopper to the frame;

Figure 6 is a section on the line 6—6 of Figure 4.

Referring now more particularly to the drawings, the numeral 10 indicates the standards, 11 the side members and 12 the end members of a frame. In accordance with my invention, I provide three parallel shafts 13, 14 and 15, which are mounted in bearings carried by the side members. The shaft 13

is provided upon its opposite ends with pulleys 16 and 17 and has secured thereto inwardly of the pulley 17 a small gear 18. The end of the shaft with which the pulley 16 is engaged is extended beyond this pulley and adapted, as at 19, for engagement with a handle, whereby it may be rotated. The shaft 14 has secured thereto a gear 20 of greater size than and meshing with the gear 18, so that the shaft 14 will be rotated at a slower rate of speed than the shaft 13 when driven therefrom. Between its bearings, the shaft 14 has secured thereto a roll 21 to the periphery of which is secured a metallic sheet 22 having burrs 23 upon the outer face thereof formed by punching the sheet from its inner face with a blunted instrument. Other means of producing these burrs may be employed, if desired. The shaft 15 has secured thereto intermediate its bearings a roll 24 having secured thereto a sheet 25 having burrs similar to the burrs of the sheet 22. One end of this shaft is provided with circumferential series of spaced sockets 26 adapted to receive the inner end of a set-screw 27 directed through the encasing bearing cap 28, so that this shaft may be held against rotation in adjusted positions.

Secured to the side members 11 between the bearings of the shafts 14 and 15 are feet 29 formed upon the lower ends of the vertical side walls 30 of a hopper 31. The end walls of this hopper, indicated at 32, converge downwardly and have their lower ends in close proximity to the upper surfaces of the rolls 21 and 24 respectively.

The mechanism just described is arranged at one end of the frame and beneath the frame at the opposite end thereof is disposed a separator 33 for separating nuts and the hulls thereof. The operating shaft 34 of this separator is provided with a pulley 35 aligning with and connected to the pulley 17 by a belt 36. A chute is provided for leading the hulled nuts and their hulls from the rolls 21 and 24 to this separator, this chute having an inclined bottom 37, the upper end of which is extended into close proximity to the lower surface of the roll 24. From this roll, the

chute inclines downwardly to the separator passing beneath the roll 21.

In operation of the machine, the shaft 13 is rotated either by power applied to this 5 shaft or by means of a crank. The nuts to be hulled are placed in the hopper 31 and by rotation of the roll 21 and engagement with the burrs 23 thereof, will be forced into contact with and rolled against the burr plate 10 25 of the roll 24. This rolling action readily ruptures the brittle hulls of the nuts and by the maintenance of sufficient space between the rolls, any crushing of the nuts themselves is avoided. As the teeth of the operating section 15 of the roll 24 become dulled or ineffective, a fresh working surface may be presented by releasing the set-screws 27 and partially rotating the shaft and its roll. The nuts and their crushed hulls will be delivered to the 20 chute 37 and from this chute to the separator 33.

Since the construction hereinbefore set forth is capable of a certain range of change and modification without materially departing from the spirit of the invention, I do not 25 limit myself to such specific structure except as hereinafter claimed.

I claim:—

30 In a nut sheller for pinon nuts and the like, a pair of rolls, a removable covering for the rolls providing the rolls with a burred periphery, the rolls having their adjacent faces spaced, a shaft upon which one of the rolls is mounted, bearings for said shaft, the shaft 35 within one of the bearings having a circumferential series of spaced sockets, a screw adjustable through the cap of the said one of the bearings for selective engagement in said sockets to hold said shaft against rotation and means for rotating the other of the 40 rolls.

In testimony whereof I hereunto affix my signature.

JAMES G. BAUDINO.
